Application January 27, 1940, Serial No. 315,889

18 Claims.

(Cl. 60—53)

This invention relates to timing devices for power transmission systems and has particularly to do with a hydraulic timing control system.

The need for accurate control of power driven machinery especially in machine tool drives is well recognized. The present invention has for its object the provision of a precision timing arrangement especially adapted for hydraulic transmission equipment for machinery and machine tools and other types of control where accuracy is required. In those particular systems in which it is the practice to have a slow moving drive shaft and an output shaft which makes several revolutions to one revolution of the drive shaft, it will be seen that a small deviation in the timing device at the drive will be greatly multiplied at the output. In many cases the timing control must be connected to the drive and consequently it is essential that it be accurate.

It is a further object of the present invention to provide a timing arrangement in which the output shaft of a control system may be stopped within a few degrees of the same point in each cycle. An added feature of the device is that it may be adapted to practically any type of power system and certain objects of the invention have to do with the combination of the basic timing control with various hydraulic power systems.

Briefly, the invention consists of introducing into a hydraulic circuit two or more interconnected timing valves which are actuated from a power shaft. These valves are preferably arranged to be shifted by said shaft at different rates of movement so that at one particular point in a cycle of movement, each of the valves will have reached a definite control position which will produce a response in the system and cause a change in the operation of the driving shaft. This change may either be a stopping or a reversal or, in some cases, it might be simply a change in speed. The present invention is particularly useful in devices having long or continuous operation in which the oil heats and becomes thin. With a single counter-valve control, as the valve approaches stop position there may be leakage which will cause premature stopping or change of direction. With the provision of a "tripper" valve as well as the "counter" valve, the tripper serves as a check or seal for which the change in action should take place.

Other objects and features of the invention relating, for example, to details of hydraulic system in which the control of the present invention may be embodied, will be brought out in detail in the following description and claims.

In the drawings:

Fig. 1 is a sectional view of a hydraulic circuit

illustrating the passageways in a single plane for purposes of disclosure and showing the timing control.

Fig. 2 is a sectional view on the lines 2—2 of Fig. 1.

Figs. 3 and 4 are additional views of the system of Fig. 1 showing the parts in different relative positions.

Fig. 5 is a sectional view of a hydraulic system 10 in which a pressure backed relief valve is utilized to control a pressure source and the timing control valves of the present invention are used in cooperation therewith.

Fig. 6 is a view similar to Fig. 5 showing the parts in different relative positions.

Fig. 7 is a partial view of the device shown in Fig. 5 illustrating a valve in a shifted position.

Figs. 8 and 9 illustrate the invention embodied 20 in a hydraulic control system in which a directional control valve is utilized, the timing control being arranged to effect an automatically oscillating cycle in the shifted member.

Figs. 10, 11 and 12 illustrate various portions 25 of the system shown in Figs. 8 and 9 with the movable parts in different relative positions.

Fig. 13 illustrates the invention embodied in a hoisting control which has a gravity movement in one direction.

Figs. 14, 15 and 16 illustrate a part of the 30 circuit of Fig. 13 showing the valve in its respective positions.

Fig. 17 illustrates another hydraulic system in which the invention is embodied to permit control for two directions of movement.

Figs. 18 and 19 are developments of Fig. 17 showing a valve in its respective positions.

Fig. 20 is a partial view of Fig. 17 showing the 40 relationship of the control valves during a part of the cycle.

Figs. 21 and 22 illustrate the invention embodied in a system in which the power element is controlled by a variable displacement pressure source.

An illustrative embodiment of the invention is 45 shown in Figs. 1 to 4. Referring to these figures, it will be seen that a pump 25 furnishes liquid under pressure to a motor 26 through a pressure conduit 27. The motor 26 is mounted in the side

50 of a tank 28 which is adapted to contain liquid, usually oil, to be used in the pressure system. A drive shaft 29 of the motor passes through the tank 28 and is mounted at its outer end in a bearing 30 in the wall of the tank. The protruding portion 31 of the shaft is adapted to be connected to the means to be driven. The motor 26 is provided with an outlet 32 which leads to a valve block 33 mounted on the top of the tank.

In this valve block are three valves 34, 35 and 36.

60 The valve 34 may be designated as a means for

controlling the operation of the motor 26 since it is shiftable from a position shown in Fig. 1 to a position shown in Fig. 4 to block the flow of liquid from the conduit 32, this flow normally passing to a tank conduit 37. A spring 38 urges the valve 34 to its closed position shown in Fig. 4. When the valve 34 is shifted to its closed position, locking the tank conduit 37 from the exhaust conduit 32, the pump will deliver pressure to the tank through the relief valve 39. The valve 34 is also adapted to be controlled by pilot pressure which has its source in a conduit 40 leading from conduit 27. This conduit 40 leads through a needle valve 41 to a chamber 42 above the valve 34. Pressure in this chamber will shift the valve 34 to its open position as shown in Fig. 1.

Valves 35 and 36 are provided to control the pilot pressure in chamber 42. Each of these valves is adapted to have an open and closed position. When the valve 35 is in its open position, as shown in Fig. 1, it will connect a conduit 43 leading from chamber 42 to a conduit 44 leading to valve 36. When the valve 36 is in open position, as shown in Figs. 3 and 4, the conduit 44 will be connected to a conduit 45 leading to the tank. It will thus be seen that when both valves 35 and 36 are in open position, the chamber 42 will be open to the tank thus relieving the pressure therein. This will permit spring 38 to shift the valve 34 to its closed position.

Valves 35 and 36 are each arranged to be shifted by cams 46 and 47, respectively. Cam 46 is operatively connected to shaft 29 by a screw 48 which is arranged to revolve the cam 46 once in a predetermined number of revolutions of the shaft 29. The cam 47 is operatively connected to the shaft 29 by a screw 49 which is arranged to revolve cam 47 once in every revolution of the shaft 29. Springs 50 and 51 urge the valves 35 and 36 respectively against the cams. Each of the valves is provided, respectively, with a follower 52 and 53. A lever 54 pivoted at 55 serves to permit manual operation of the valve 36 in a manner which will be later described. Suitable conduits are provided to vent the ends of valves 35 and 36.

A latching means for the shaft 29 is also arranged to be controlled by pilot pressure. This means consists of a wheel 56 (Fig. 2) which is provided with a notch 57. A bell crank 58 is provided with a dog-end 59 which may be received by the notch 57. Through suitable linkage a piston 60 is connected to the bell crank 58. The piston 60 is located in a cylinder 61 and a spring 62 urges the piston to the left as viewed in Fig. 2. The left end of the piston 60 is connected by a conduit 63 to conduit 43 so that the pressure in the chamber 42 will at all times, be exerted on the piston 60. It will be understood that the parts above described in connection with the latching or locking means 56 and 59 may be formed with sufficient strength including the spring 62 so that the motor will be locked in position when pilot pressure is not exerted against the piston 60. The requirements of the particular transmission system will determine the strength which these parts will be formed for.

In the operation of the device above described, assuming that the parts are in the positions shown in Fig. 4, the pump 25 will be bypassing pressure through the relief valve 39 and the pilot pressure which is maintained in the conduit 27 will be passing through the needle valve 41 and to the tank through conduits 43, 44, and 45. To start the motor, the operating lever 54 must be

10 moved to its top position shown in dotted lines. This will shift the valve 36 upward so that the conduit 44 will be cut off from conduit 45 and from the tank. Pressure will then build up in the chamber 42 and also in the conduit 63 and cylinder 61. When this pressure has reached a predetermined point, valve 34 will be shifted against the spring 38 to the position shown in Fig. 1 and the piston 60 will be shifted against the spring 62 to the position shown in Fig. 2, thus permitting the dog 59 to be withdrawn from the notch 57.

15 As soon as the valve 34 is shifted by the pilot pressure in chamber 42, the exhaust conduit 32 of motor 26 will be open to the tank and the motor will be operated by pressure from the pump. The valve 36 must be held in its upper position for a certain length of time to maintain conduit 45 blocked until a cam portion 46a on cam wheel 46 is shifted out from under the follower 52. This will permit the spring 50 to shift the valve 35 to its closed position, as shown in Fig. 3. During each revolution of the shaft 29, the valve 36, which may be called a "tripper" 20 valve, will be shifted by cam portion 47a on cam 47 from the position shown in Fig. 1 to the position shown in either Figs. 3 or 4. After a predetermined number of revolutions of the shaft 29, depending on the ratio of the connection between the shaft and the cam 46, the valve 35, 25 which may be called a "counter" valve, will also be shifted by cam portion 46a to its open position, as shown in Fig. 1. In Fig. 1 the cam wheels 46 and 47 are in motion and nearing the end of a cycle. It will be seen that the cam member 46a has reached its top position and the cam 47 is approaching its top position. As yet, the tank line 45 is cut off from the line 44 so that the chamber 42 is still cut off from the tank. As 30 soon as the cams are moved to the respective positions shown in Fig. 4, it will be seen that the chamber 42 is open to the tank and consequently the spring 38 will move valve 34 to its closed position thereby blocking movement of the motor. At the same time the venting of the chamber 42 vents the pressure in conduit 63 and the piston 60 is moved to the left as viewed in Fig. 2 by the spring 62. When cams 46 and 47 have arrived at their Fig. 4 position, the pressure in line 63 and chamber 42 has been released, 35 and valve 34 has been moved upward by spring 38 to thus close off passage 37. By the release of pressure in line 63, spring 62 has moved piston 60 to the left to oscillate lever 58 to the left. At this time, the notch 57 of wheel 56 is in such a position that dog-end 59 will engage therein.

40 As the parts are viewed in Fig. 3, the mechanism is shown in operation with the follower 52 riding on the wheel 46 and the valve 35 in closed position. As will be understood from the above description the valve 36 reaches the open position shown in Fig. 3 once in every revolution of the shaft 29.

45 In Figs. 5, 6 and 7, there is illustrated the combination of the above described timing control with a system in which a hydrostatic relief valve is utilized. In this system a pump 70 furnishes liquid under pressure to a feed conduit 71 which leads to a directional control valve 72. This valve has two ports opening respectively to conduits 73 and 74 which, in turn, lead to a reversible motor 75. Tank outlets 76 and 77 also open to ports surrounding the valve and lead to a tank connection 78.

50 Arranged to bypass the feed line 71 is a line

79 which may be closed by a hydrostatic valve 80. This valve 80 is actuated by a piston 81 which is formed integrally with the valve. A spring 82 normally urges the valve to its closed position and behind the valve is formed a pressure chamber 83. A relief valve 84 is exposed to the pressure chamber 83 and arranged to divert pressure liquid to the tank when it reaches a certain predetermined limit. The feed line 71 is connected to the pressure chamber 83, in this case, through a restricted opening 85 in the piston 81 so that it may be said that the pressure chamber 83 receives pilot pressure from the feed line through the restricted orifice 85.

In this system, shown in Fig. 5, the controlling element for the operation of the system is the valve 80 which, when backed by pressure in chamber 83, will maintain the bypass conduit 79 closed and thus permit pressure to be directed from the pump to the motor 75 through the directional control valve 72. It will be seen that the directional control valve may be shifted to direct pressure to either line 73 or 74 and thus control the direction of rotation of the motor. The motor in this case drives a shaft 86 and is mounted in a tank 28a in the top of which is a valve housing 33a. The shaft 86 passes through the wall of the tank and is provided with a locking wheel 56 as in connection with the embodiment of Fig. 1, with suitable latching means being shown as described in connection with Fig. 2. The conduit 63 for controlling the piston 60 of the latching means is connected in Fig. 5 to a conduit 87 which leads from the pressure chamber 83 to a control valve 88 located in the housing 33a. A second control valve 89 is also located in the housing. The pressure chamber 83 is adapted to be bypassed to the tank through the conduit 87, past the valve 88, through a conduit 90, and past the valve 89 to a conduit 91. The valve 88 has an open position as in Fig. 5 and a closed position as in Fig. 7. Similarly valve 89 has a closed position as in Fig. 5 and an open position as shown in Fig. 6. The valve 88 is also arranged to restrict the exhaust flow through the tank conduit 78 as it passes to line 92. This will cause deceleration of the motor 75 and it will be seen that this restriction takes place as the valve is moved to its open position as above described.

The operation of the system shown in Figs. 5 and 6 is similar to that disclosed in connection with Fig. 1. The "counter" valve 88 and the "tripper" valve 89 are shown as being operated by the shaft 86 through worm gears 48 and 49 operating cam wheels 46 and 47, respectively, with a one to one ratio between the shaft 86 and the cam 47 and a predetermined ratio between the shaft 86 and the cam 46. As the parts are shown in Fig. 5, the motor has been operating by receiving pressure from pump 70 through line 71, valve 72 and line 74. Tank flow from the motor is passing through line 73, valve 72 and line 78. As the valves are shown, valve 88 is moved to its open position and is gradually restricting the flow from line 78 to line 92, thus causing a deceleration of the motor. Slits 93 are provided in the valve 88 to permit this gradual restriction in the exhaust flow. At this time the valve 89 is in its closed position but as the revolution is completed the cam 47 will shift the valve 89 to its open position as shown in Fig. 6. At this time the pressure chamber 83 will be relieved or vented through lines 87, 90 and 91 and the pressure in the feed line 71 will move the piston 81 upwardly. This movement is due to the fact

that pressure cannot reach the chamber 83 through the restriction 85 as fast as it can pass through the venting lines as above described. The opening movement of the valve 80 (Fig. 6) will bypass the flow from the pump 70 through line 79. The operation of the latching means 58 is the same as described in connection with Fig. 2, the pressure against piston 60 being dependent on the pressure in the chamber 83. The pressure in the entire system is limited by the valve 84, which will open at a predetermined point. The operation of the system is the same if the valve 72 is shifted to the right so that pressure from line 71 may reach the line 73. The operation of the motor will then be reversed but the timing arrangement will function in the same manner. The system may be started by raising the valve 89 with the lever 54.

In Figs. 8 through 12 is illustrated a hydraulic control system in which the invention has been arranged to effect automatic oscillating cycles. In this system a pump 100 furnishes liquid through a conduit 101 to a directional control valve 102 which in turn directs liquid to a reversible motor 103 through either conduit 104 or 105 depending on the position of the control valve 102. If pressure is being directed to conduit 105, as in Fig. 8, exhaust pressure will be delivered from conduit 104 through the control valve 102 to a tank conduit 106. If the valve 102 is shifted as shown in Fig. 9, pressure will be directed through conduit 104 to the reversible motor and exhaust liquid will flow from conduit 105 to tank conduit 106. The operation of the entire system is to be controlled by a manually operated valve 107 controlled by hand lever 108. A bypass valve 80 is provided, as before in Fig. 5, and the chamber 83 of this valve is connected through a conduit 109 to the valve 107. When the valve 107 is in the position shown in Fig. 8, conduit 109 is blocked from the tank but when valve 107 is shifted to the position shown in Fig. 12, conduit 109 will be open to a tank conduit 110 thus relieving the pressure in chamber 83. A relief valve 84 is also hydraulically connected to the chamber 83. Relieving of the pressure in chamber 83 will permit the pressure in conduits 101 to open the valve, as shown in Fig. 12, and thus bypass liquid under pressure to the tank through a conduit 111. At the respective ends of valve 102 are formed chambers 112 and 113 for receiving pilot pressure to cause shifting of the control valve 102.

"Counter" valve 114 and "tripper" valve 115 are used to control the system. The control valve 114 is arranged to be shifted to direct pressure to either a conduit 116 leading to chamber 112 or a conduit 117 leading to chamber 113. Pressure in these conduits is received from a conduit 118 leading from the valve 115 and pilot pressure is connected to the valve 115 by a conduit 119 leading from pressure conduit 101. With the valve 115 in the position shown in Fig. 8, pressure is blocked in conduit 118 so that it may not pass to conduit 116 and to the valve 115. If, however, the valve 115 is moved to the position shown in Fig. 9, the pressure may pass from the conduit 119 to conduit 118 in the valve 114. Each of the valves 114 and 115 is provided with a follower 120 and 121, respectively. The follower 120 rides on a cam 122 which is driven through a shaft 123 and a screw 48 and wheel 124 from a motor shaft 125. Similarly, the follower 121 rides on a cam 126 which is driven in a one to one ratio from shaft 125 by a screw 49. A cam portion 126a is

formed on the cam 126 to cause a lifting of the valve 115 to the position shown in Fig. 9, once in every revolution of shaft 125.

The cam 122 has a peculiar shape. It will be noted that a portion of the cam is circular. Another portion has a projection 127 which projection will serve to move the valve 114 to the positions shown in Figs. 8 and 9. A recessed portion 128 is also provided and when the follower is on this portion, the valve 114 will be in the position shown in Fig. 10. When the follower is on the circular portion of the cam, the valve 114 will be in the position shown in Fig. 11.

With the cams and the valves in the position shown in Fig. 8, it will be seen that the projection 127 on cam 122 has just shifted the "counter" valve 114 to the position in which pressure may pass from conduit 118 to conduit 117. "Tripper" valve 115, however, is still in a position where pilot pressure is blocked from conduit 118. As soon as valve 115 is moved by cam portion 126a to the position shown in Fig. 9, pilot pressure may pass from conduit 119 to conduit 118 and thence past valve 114 to conduit 117 and chamber 113. This will cause a shifting of valve 102 to the right and, consequently, the direction of flow of motor 103 will be reversed. At the end of the next cycle the follower 120 will be on the recessed portion 128 of cam 122 as viewed in Fig. 10. At this time, the conduit 118 is open to conduit 116 which leads to chamber 112. At a certain time in the revolution of shaft 125, the valve 115 will be shifted to the position shown in Fig. 9, at the same time as the valve 114 is in the position shown in Fig. 10. Pilot pressure may then pass from conduit 119 to conduit 118 and conduit 116 and thence to chamber 112, again shifting the valve 102 to the position of Fig. 8. This oscillation will continue until the lever 108 is moved so that the chamber 83 of valve 80 is vented. The system will then stop. It will thus be seen that an automatic oscillating cycle has been provided and the cam 122 will be geared to the shaft 125 in such a way that a predetermined number of revolutions will take place during the time that the cam is passing from a position such as shown in Fig. 8, to a position shown in Fig. 10.

In Fig. 13, the invention is shown adapted to a hoisting system. In this system, a hoisting motor 130 is to be driven in a hoisting movement by pressure from a pump 131. On a motor shaft 132 is located a hoist wheel 133. A cable 134 wraps around this wheel 133 and supports a weight 135 to be lifted and lowered. At the other end of the shaft 132 is a brake drum 136 and a screw 137. A brake member 138 is adapted to contact the drum 136 to hold the shaft 132 from rotating. This brake member is connected to a piston 139 and is urged toward the drum 136 by a spring 140. A conduit 141 leads to a chamber below the piston 139 and it will be seen that pressure in this conduit will urge the piston 139 against the spring 140.

Pump 131 delivers liquid under pressure to a conduit 145. A valve 80 is here provided to bypass this conduit to a tank conduit 146 when pressure is vented from the chamber 83, backing the valve 80 as described in connection with Fig. 5. Pilot pressure is derived from conduit 145 and the restriction 85 in the valve. Conduit 145 also leads to a directional valve indicated generally at 147. The motor 130 is connected to the valve 147 by conduits 148 and 149. Pilot

pressure for controlling the system is directed from a conduit 150 connected to chamber 83 to the valve 147. Another control valve 151 has conduits 152 and 153 leading also to the valve 147. A follower 154 on valve 151 rides on a cam 155 which is geared to the shaft 132 in a one to one ratio.

An extension 156 on valve 147 has a slideable member 157 thereon, the movement of which is limited by adjustable nuts 158 and 159. The member 157 is connected through a lever 160 to a nut 161 which screws on the screw member 137.

It is believed that the details of the valves 147 and 151 can best be brought out by describing the operation thereof in connection with the system. As the parts are viewed in Fig. 13, the equipment is hoisting the weight 135 and nearing the end of the hoisting movement. Pressure is flowing from conduit 145 to the conduit 148 as may be clearly viewed in Fig. 16. As the hoisting movement reaches completion, it will be seen that the movable member 157 is being shifted to the left, Fig. 13, and the valve 147 is following this movement caused by rotation 25 of the screw 137 in the nut 161. At the particular point illustrated in Fig. 13, it will be seen that, while pilot pressure may pass from conduit 150 to conduit 152, past a restriction in valve 147, pilot pressure may not pass to conduit 153 because of the position of valve 151. Conduit 153 is connected to a tank conduit 162. Meanwhile, the flow from conduit 145 is gradually being cut off from conduit 148 and the valve 147 is provided with slots 163 to permit restricted flow. Valve 35 80, in connection with relief valve 84, is an effective relief valve which will permit by-passing of a certain amount of volume from pump 131 as the passage from line 145 to 148 is gradually restricted. As the hoisting movement comes to an end the cam 155 will shift the valve 151 downward so that conduits 152 and 153 are connected. This will permit a venting of chamber 30 83 and, consequently, pressure in conduit 145 will open valve 80 and cause a by-passing of 35 pump output. At the same time conduit 145 is closed from conduit 148 by valve 147 to prevent 40 45 lowering.

It will be seen at this time that as soon as chamber 83 is vented, the conduit 141, connected 50 to conduit 150, will also be vented thus permitting spring 140 to move the brake member 148 against drum 136. The line 153 is closed, as shown in Fig. 16, when lever 164 is in hoist position. However, at the end of the hoisting, the 55 entire valve will be shifted so that this line is open simultaneously with the by-passing of lines 150 and 152.

To effect a lowering movement of the motor 130, the valve 147 is shifted to the left by a manually operable lever 164. This position is shown 60 in Fig. 14. At this time it will be seen that a branch conduit 165 leading from conduit 148, is connected to conduit 149 so that liquid coming from the motor in its reverse movement may pass 65 again into conduit 149. During this cycle the motor functions as a pump and a low pressure foot valve 166 resists the return of oil to the tank thus constraining the circulation of oil to the motor circuit during the lowering cycle. Without this foot valve a partial void would tend to operate in the system and irregular operation would result. The shifting of valve 147 to the 70 75 position shown in Fig. 14 will cut off conduit 150 from conduit 152 but will connect it to a relief

valve 167. This relief valve is set to sustain pressure in conduit 150 just sufficient to cause releasing of the brake member 138. However, the valve 167 will still permit tank flow at a greater rate than flow may take place through restriction 85 of valve 80 so that the pump 131 is unloaded at this time.

During the lowering operation, the valve 147 will remain in its "lower" position (Fig. 14) until the movable member 157 is shifted to the right to contact nut 159; there will then be a movement of the valve 147 to the right gradually restricting and finally blocking the flow through conduit 165, thus bringing the hoisting motor 130 to rest. The final movement of valve 147 will again connect the conduit 150 with conduit 152 and the timing valve 151 so that chamber 83 is again vented at a predetermined point in a revolution and the brake 138 applied.

To start the hoisting operation once more, the valve 147 is shifted to the position shown in Fig. 16. This will block conduit 150 from conduit 152 and consequently, cause a building up of pressure in the hydrostatic chamber 83. Consequently, pump 131 may again deliver liquid from conduit 145 to conduit 148 and simultaneously the brake 141 will be released.

In Fig. 17, the invention is shown embodied in a hydraulic system which is reversible and in which the timing control may be used for movements in both directions. Referring to Fig. 17, a motor 170 drives a main pump 171 and a pilot pump 172. The main pump 171 is adapted to furnish pressure to a reversible motor 173 through a conduit 174 and conduits 175 and 176. A directional control valve 177 is interposed in these conduits for directing pressure from conduit 174 to either conduit 175 or 176, the other being connected simultaneously to the tank. At the left end of valve 177 is a centering device 178 adapted normally to maintain the valve in a central or neutral position. In the central position, the pump 171 is by-passed to the tank through central passageways in the valve 177. A relief valve 179 limits the pressure in the conduit 174. At the right end of the valve 177 extends a rod 180 into a chamber 181. On this rod is a piston 182.

The pilot pump 172 delivers pilot pressure into a conduit 185 and thence to a directional control valve 186. This valve is to be manually operated by a lever 187. Two conduits 188 and 189 connect the valve 186 with opposite sides of piston 182 in chamber 181. When the valve 186 is in the position shown in Fig. 17, pilot pressure may be directed to piston 182 through the conduit 188 to shift valve 177 to the left as shown. When valve 186 is moved to the position shown in Fig. 19, pilot pressure is then exposed to conduit 189 and the left side of piston 182 so that valve 177 will be shifted to the right and reversal of the motor will take place. Valve 186 also has a neutral position as shown in Fig. 18. In this position, both ends of piston 182 are vented to the tank through conduit 190, thus allowing valve 177 to be returned to neutral by its centering spring. In this manner, the flow from pump 171 is diverted to tank and the motor stops. It will be further noted that when valve 186 is in the position shown in Fig. 18, pressure conduit 141 is also vented to the tank. Conduit 190 connects two ports of valve 186 to the tank so that when one end of the cylinder 181 is connected to pressure, the other end will be connected to the tank.

A check valve 185a is placed in line 185 to relieve the pump 172 after piston 182 is shifted and valve 186 is in a position shown either in Fig. 17 or 19.

So far there has been described in Fig. 17, a pilot operated directional control valve with a pilot valve for operating the same. Referring now to the timing control, it will be seen that leading from conduit 188 is a conduit 191 which opens to a port surrounding a valve 192. Similarly, leading from conduit 189 is a conduit 193 leading to a port surrounding a valve 194. Between the valves 192 and 194 is a conduit 195. Leading from valve 194 to a third timing control valve 196 is a conduit 197. Each of the valves 192, 194 and 196 is provided with followers which ride respectively on cams 198, 199 and 200. Cams 198 and 199 are each connected to a motor shaft 201 on motor 173 in such a way that they will make one revolution for a predetermined number of revolutions of the shaft 201. Cam 200 is connected to shaft 201 in a one to one ratio so that cam 200 revolves once for every revolution of shaft 201.

As the parts are shown in Fig. 17, the motor is completing a movement in one direction. Cam 198 has just shifted valve 192 upwardly so that conduits 191 and 195 are connected to conduit 197 which is blocked by valve 196. A slight further movement of shaft 201 in its present direction will move cam 200 so that valve 196 will be shifted to the position shown in Fig. 20.

By reason of this movement, the right side of piston 182 will be connected to the tank through conduits 188, 191, 195, 197 and a tank line 202. This venting of the right side of piston 182 will allow the centering device to move valve 177 to neutral position.

When movement of motor 173 in the other direction is desired, the lever 187 must be moved to the position shown in Fig. 19. Pilot pressure will then be directed from conduit 185 to conduit 189 and the valve 177 will be shifted to the right. Rotation of cams 198, 199 and 200 will then be in the opposite direction to the arrows shown in Fig. 17 and at the end of the movement of the motor in this direction, the cams will be positioned as shown in Fig. 20. In this position, it will be seen that conduit 193 is connected to the tank past valve 194 and through conduit 197 and conduit 202. This will vent pressure from the left side of piston 182 and cause a return of valve 177 to neutral. The brake is provided on the shaft 201 as described in connection with Fig. 13. A conduit 141 leads from the pressure conduit 185 to piston 139 which controls a brake member 138 moved by spring 140 to braking position with a drum 136 on shaft 201 when pressure in 141 is relieved.

The gear ratio of drive for cams 198 and 199 is the same but these cams are arranged out of phase with each other so that valves 192 and 194 are not opened at the same time. This permits each of the valves 192 and 194 to cooperate individually with valve 196.

In Figs. 21 and 22 the invention is illustrated in connection with a hydraulic system which utilizes a variable displacement pump as a source of pressure. This pump, shown at 205, has a tilting block 206, the position of which controls the output of the pump. A motor 207 drives this pump and also, through gear train 208, drives a pilot pump 209. A relief valve 210 is provided in a conduit 211 leading from the pump 205 to a motor 212. Another conduit (not shown) is pro-

vided to conduct the return flow from the motor 212 to the pump. Whether or not the pump 205 delivers liquid to the motor will depend on the position of the tilting block 206. Through suitable linkage 213 a piston 214 is connected to the tilting block 206. This piston is located in a chamber 215 and a spring 216 urges the piston downwardly and tends to move the tilting block to a neutral or non-volume position.

Pilot pressure from pump 209 is connected by a conduit 217 to chamber 215. When this pilot pressure is maintained against piston 214, there will be a volume output of pump 205 and a movement of motor 212. A venting of this pilot pressure to the tank will cause the spring to move the tilting block 206 to its neutral position and cause a stopping of the motor. The pilot pressure is controlled by a timing valve 218 and a timing valve 219. The valve 218 has a follower which rides on a cam 220 which rotates once in a predetermined number of revolutions of a shaft 221 on motor 212. Valve 219 has a follower which rides on a cam 222 which rotates once for every revolution of shaft 221. Conduit 217 is connected to valve 218 by a conduit 223 and with valve 218 in the position shown in Fig. 21, the conduit 223 is connected to a conduit 224 leading to valve 219. With valve 219 in the position shown, conduit 224 is blocked from a tank conduit 225 but a movement of valve 219 to the position shown in Fig. 22, will connect conduit 224 to the tank conduit 225.

Referring now to the operation of this system of Fig. 21, it will be seen that as the parts are viewed in the drawings, cam 220 has just shifted valve 218 to connect conduits 223 and 224. As cam 222 completes its revolution and moves to a position shown in Fig. 22, valve 219 will be lifted and there will be a venting of pressure in chamber 215 through the conduits shown to the tank conduit 225. In Fig. 22, the valve 218 is shown in its closed position as it normally rides on cam 220 and valve 219, as before mentioned, is shown in its open position. To start the system, after it has been automatically stopped, a manually operable lever 226 may be used to shift valve 219 upward to block the tank conduit 225 temporarily. As soon as valve 219 rides off the lobe of cam 222, the manual lever 226 may be released since conduit 224 will be caused to be blocked from conduit 225 by the spring of valve 219 moving it downwardly as shown in Fig. 21. Blocking of conduit 224 will, of course, cause pressure to build up in chamber 215 and start the volume output of pump 205. Just before cam 222 completes its first revolution, the lobe of cam 220 will have advanced to a point where it allows valve 218 to lower and block conduit 223. A brake similar to that shown in Figs. 13 and 17 is also shown in connection with Fig. 21.

In each of the above modifications, embodying the invention, the object is to achieve accurate control of a moving member. In each of the above illustrations this has been accomplished by arranging the timing control valves so that they are responsive in a different degree to the movement of a member. The invention has numerous applications. It might also be arranged to control a member having longitudinal movement, suitable connections being provided between the timing valves and the member.

I claim:

1. In a power system including motor means to be operated in a predetermined cycle, a con-

trol circuit for said motor means including a pressure control line operatively connected to said means, and arranged, when open, to stop said power system, a counter-valve in said line connected to said means in a manner to be operated once during said cycle, and a tripper valve in said line connected to said means in a manner to be operated a predetermined number of times in said cycle, each of said valves being connected in series in said line and arranged, when simultaneously operated, once in each cycle, to open said line.

2. In a hydraulic control system, a hydraulic motor, a source of fluid pressure therefor, a source of pilot pressure, means responsive to said pilot pressure for controlling the movement of said motor, and means for controlling said pilot pressure comprising a plurality of valve means in series hydraulically, means operating said valves a different number of times relative to a predetermined movement of said motor, said valves being arranged to operate simultaneously at the end of a predetermined movement of the motor and cooperating to influence the effect of pilot pressure on said first named means after said predetermined movement of said motor.

3. A timing device for accurately measuring and limiting the operating cycle in a hydraulic transmission system comprising a hydraulic motor intended to have a predetermined cycle of operation, a source of fluid pressure for said motor, and means for determining the cycle of operation of said motor comprising a plurality of valve means actuated by motor movement, operatively connected to a control circuit for said motor, and cooperatively arranged to have an effect on said control circuit when correspondingly positioned, one valve means being operated relatively slow and the other or others being operated faster whereby at a predetermined point in the movement of said motor, the valves will each be correspondingly positioned to affect said circuit to change the movement of said motor.

4. A timing device for accurately measuring and limiting the operating cycle in a hydraulic transmission system comprising a hydraulic motor and output shaft therefor, intended to have a predetermined cycle of operation, a source of fluid pressure for said motor, means for controlling the movement of said motor, and means in a control circuit for said motor comprising a plurality of valve means in series in a pressure line, each adapted in a certain position to have the same effect on said line, and means operatively connecting said valves and said output shaft arranged to operate said valves at different speeds and arranged at a predetermined point in the cycle of movement to position said valves to have said corresponding effect on said line and to change the movement of said motor.

5. In a hydraulic control system, a motor, a source of pressure, means to control said pressure and the movement of said motor comprising a plurality of valve means, each responsive to a different degree to the movement of said motor and cooperating at a predetermined point in the movement of said motor to influence the effect of said pressure on said motor whereby the movement of said motor may be accurately controlled.

6. In a hydraulic control system, a motor, a source of pressure for operation of said motor, a source of pilot pressure, means responsive to said pilot pressure for controlling the movement of said motor, and means for controlling said pilot pres-

sure comprising a plurality of valve means hydraulically connected in series with said first named means and each movable to a position whereby they cooperate to control the effect of said pilot pressure on said responsive means, each of said valve means being responsive in a different degree to the movement of said motor and each arranged to be shifted, at a predetermined point in the movement of said motor, to a position whereby the effect of pilot pressure on said first named means is changed.

7. In a hydraulic control system, a motor, a source of pressure, means for controlling said pressure and the movement of said motor comprising a first control valve connected to said pressure, a second control valve movable to an open position to direct pressure from said first valve to a tank, said first valve being movable from a closed position to an open position connecting said pressure with said second valve, and means connecting said motor with said valves whereby movement of said motor will cause movement of said valves, said connecting means being so arranged that at a predetermined point in the movement of said motor, each of said valves will be in open position to render said pressure ineffective to operate said motor.

8. In a hydraulic control system, a source of pressure, a motor to be operated by pressure from said source, a source of pilot pressure, means for controlling the movement of said motor comprising a motor control valve in the exhaust of said motor shiftable from a closed position in which said exhaust is blocked to an open position in which said exhaust is free, means urging said motor control valve to one of its positions, a pilot line directing pilot pressure to said motor control valve to shift the valve to the other of its positions, a bypass line leading from said pilot line adapted, when open, to render said pilot pressure ineffective to shift said motor control valve, and a plurality of valve means in said bypass line each movable from a position closing said line to an open position, and means connecting said motor with said valve means whereby movement of said motor will shift said valve means to open position at varying intervals, said connecting means being so arranged that at a predetermined point in the movement of said motor, the pilot pressure in said bypass line will be influenced thereby thus permitting said motor control valve to shift to closed position.

9. In a hydraulic control system, a source of pressure, a motor to be operated by pressure from said source, a source of pilot pressure, means for controlling the movement of said motor comprising a motor control valve in the exhaust of said motor shiftable from a closed position in which said exhaust is blocked to an open position in which said exhaust is free, means urging said motor control valve to one of its positions, a pilot line directing pilot pressure to said motor control valve to shift the valve to the other of its positions, a bypass line leading from said pilot line adapted, when open, to render said pilot pressure ineffective to shift said motor control valve, and a plurality of valve means in said bypass line each responsive to a different degree to the movement of said motor and cooperating at a predetermined point in the movement of said motor to influence the effect of pilot pressure on said first named means whereby the movement of said motor may be accurately controlled.

10. In a hydraulic control system, a source of

pressure, a motor to be operated by pressure from said source, a source of pilot pressure, means for controlling the movement of said motor comprising a motor control valve in the exhaust of said motor shiftable from a closed position in which said exhaust is blocked to an open position in which said exhaust is free, means urging said motor control valve to one of its positions, a pilot line for directing pilot pressure to said motor control valve to shift the valve to the other of its positions, a bypass line leading from said pilot line adapted, when open, to render said pilot pressure ineffective to shift said motor control valve, and a plurality of valve means in said bypass line each movable from a position closing said line to an open position, and means connecting said motor with said valve means whereby movement of said motor will shift said valve means to open position at varying intervals, said connecting means being so arranged that at a predetermined point in the movement of said motor, the pilot pressure in said bypass line will be influenced thereby thus permitting said motor control valve to shift to closed position, and releasable means for locking said motor at a predetermined point in its movement, said releasable means being operable when said pilot pressure is so influenced as to permit the closing of said control valve.

11. In a hydraulic control system, a source of pressure, a motor to be operated by pressure from said source, a source of pilot pressure, means for controlling the movement of said motor comprising a motor control valve in the exhaust of said motor shiftable from a closed position in which said exhaust is blocked to an open position in which said exhaust is free, means urging said motor control valve to its closed position, means for directing pilot pressure to said motor control valve to shift the valve to open position, a bypass line leading from said pilot line adapted, when open, to render said pilot pressure ineffective to shift said motor control valve, and a plurality of valve means in said bypass line each movable from a position closing said line to an open position, means connecting said motor with said valve means whereby movement of said motor will shift said valve means to open position at varying intervals, said connecting means being so arranged that at a predetermined point in the movement of said motor, said bypass line will be open, thus permitting said motor control valve to shift to closed position, and releasable means for locking said motor at a predetermined point in its movement, said releasable means being operable when said bypass line is opened.

12. In a hydraulic control system, a source of pressure, a motor to be operated by pressure from said source, conduit means for directing pressure from said source to said motor, valve means shiftable from a closed position to a position wherein said pressure source is bypassed, a pressure chamber behind said valve means, a source of pilot pressure connected to said pressure chamber and normally urging said valve means to its closed position, and means for controlling said pilot pressure comprising a plurality of movable valve means each shiftable at a different rate by the movement of said motor and cooperating at a predetermined point in the movement of said motor to bypass said pilot pressure and relieve said pressure chamber thereby permitting pressure from said source to bypass.

13. In a hydraulic control system, a source of pressure, a motor to be operated by pressure from said source, conduit means for directing pressure from said source to said motor, valve means shiftable from a closed position to a position wherein said pressure source is bypassed, a pressure chamber behind said valve means, a source of pilot pressure connected to said pressure chamber and normally urging said valve means to its closed position, and means for controlling said pilot pressure comprising a plurality of movable valve means each responsive to a different degree to the movement of said motor and cooperating at a predetermined point in the movement of said motor to bypass said pilot pressure and relieve said pressure chamber thereby permitting pressure from said source to bypass, and releasable means for locking said motor at a predetermined point in its movement, said means being rendered effective by the relieving of said pilot pressure from said pressure chamber.

14. In a hydraulic control system, a source of pressure, a motor to be operated by pressure from said source, conduit means for directing pressure from said source to said motor, valve means shiftable from a closed position to a position wherein said pressure source is bypassed, a pressure chamber behind said valve means, a bypass line leading from said pressure chamber adapted, when open, to render said pilot pressure ineffective to maintain said valve means in closed position, and a plurality of valve means in said bypass line each movable from a position closing said line to an open position, and means connecting said motor with said valve means whereby movement of said motor will shift said valve means to open position at varying intervals, said connecting means being so arranged that at a predetermined point in the movement of said motor, said bypass line will be open, thus relieving said pressure chamber and permitting pressure from said source to bypass.

15. In a hydraulic control system for automatically oscillating a movable member in cycles, a motor to actuate said movable member, control means to control the direction of movement of said movable member, a source of pilot pressure, conduit means connecting said pilot pressure with said control means whereby the control means may be shifted by said pilot pressure, a directional control valve means in said conduit means adapted at one position to admit pilot pressure to shift said control means to one position and adapted in a second position to shift said directing valve to another position, a timing control valve in said conduit means shiftable from a closed position to an open position to admit pilot pressure to said directional control valve, and means operatively connecting said movable member with said timing control and said directional control valves whereby at a predetermined point in the movement of said movable member, pilot pressure will be directed to said control means to shift the same and thereby change the direction of movement of said motor.

16. In a hydraulic control system for automatically oscillating a rotating member in cycles, a motor to actuate said member, control means for controlling the starting and direction of said member, a source of pilot pressure, pressure re-

sponsive means for operating said control means, conduit means connecting said pressure responsive member with said pilot pressure whereby the pressure responsive member may be influenced by said pilot pressure to control the direction of movement of said motor, and control means for controlling pilot pressure to said pressure responsive means comprising a first valve means in said conduit means shiftable to two positions to direct pilot pressure, respectively, to opposite points to cause movement in opposite directions of said motor, a second valve in said conduit means movable from a closed position blocking pilot pressure to an open position admitting said pilot pressure to said first valve, and means connecting said movable member and said first and second valves being so arranged that said first valve is shifted from one position to another during a predetermined number of revolutions of said movable member, and said second valve is moved to open position once in every revolution of said movable member whereby said movable member is reversed in direction at a predetermined point in a revolution and after the elapse of predetermined number of revolutions in either direction.

17. In a hydraulic system, a rotatable motor, a source of fluid pressure for said motor, a source of pilot pressure, means responsive to said pilot pressure for controlling the movement of said motor, and means for bypassing said pilot pressure to nullify its effect on said first named means comprising a control line, two valves in series in said line, each movable to a closed position closing said line and to an open position opening said line, a member to be rotated by said motor and means operably connecting said member and said valves, said connecting means being so arranged that one of said valves is moved to open position once in every revolution of said member and the other of said valves is moved to open position only upon a predetermined number of revolutions of said member whereby at a predetermined point in a revolution, after the elapse of a predetermined number of revolutions, said pilot pressure will be bypassed and the operation of said motor will be changed.

18. In a hydraulic system, a rotatable motor, a source of fluid pressure for said motor, a source of pilot pressure, means responsive to said pilot pressure for controlling the movement of said motor, and means for influencing said pilot pressure to control its effect on said first named means comprising a control line, two valves in series in said line, each movable to a closed position closing said line and to an open position opening said line, a member to be rotated by said motor and means operably connecting said member and said valves, said connecting means being so arranged that one of said valves is moved to one of its positions once in every revolution of said member and the other of said valves is moved to a corresponding position only upon a predetermined number of revolutions of said member whereby at a predetermined point in a revolution, after the elapse of a predetermined number of revolutions, said pilot pressure will be influenced and the operation of said motor will be changed.
